UNITED STATES PATENT OFFICE.

REGINA L. PARENT, OF MINNEAPOLIS, MINNESOTA.

CHILD'S ONE-PIECE SLEEVELESS GARMENT.

1,332,357.

Specification of Letters Patent.

Patented Mar. 2, 1920.

Application filed September 30, 1918. Serial No. 256,202.

To all whom it may concern:

Be it known that I, REGINA L. PARENT, a citizen of the United States, residing at Minneapolis, in the county of Hennepin and State of Minnesota, have invented certain new and useful Improvements in Children's One-Piece Sleeveless Garments; and I do hereby declare the following to be a full, clear, and exact description of the invention, such as will enable others skilled in the art to which it appertains to make and use the same.

Particularly, my invention has for its object to provide an improvement in the shoulder structure of sleeveless garments that are adapted to be made from a single flat piece of cloth or from a cloth sheet that is adapted to be laid out flat before it is stitched together to form the garment. In forming the improved shoulder, a shoulder strip, which is severed from the sheet, except at one end, is turned over the shoulder and extended up to the neck of the garment, and at its edges, is stitched to the front and back upper edge flaps so as to thereby afford a shoulder, not only of neat design, but which is strong and durable and will fit snugly over the shoulders.

This improved shoulder may be applied to various different kinds of garments but is especially designed for infants' sleeveless garments, such as outdoor sleeping garments. It, however, makes the best kind of a shoulder for capes, sleeveless raincoats, or the like, for adults, as well as for children and infants.

The invention is illustrated in the accompanying drawings wherein like characters indicate like parts throughout the several views. Referring to the drawings:

Figure 1 is a plan view showing the sheet from which the body of the garment with my improved shoulder structure is adapted to be made;

Fig. 2 is a front elevation of the improved garment showing a hood also applied thereto;

Fig. 3 is a front elevation with the hood and garment opened up;

Fig. 4 is an enlarged transverse section on the line 4—4 of Fig. 2; and

Fig. 5 is a view in section taken on the line 5—5 of Fig. 2.

In Fig. 1, the numeral 6 indicates the sheet or blank from which the body of the garment is made. This sheet is made up

of a back forming portion 6^a and front forming portions 6^b and shoulder forming strips 6^c, all of which parts are adapted to be made from a single piece of cloth. When 60 the garment is large and the cloth from which it is to be made is narrow, the front forming sections 6^b and back forming section 6^a may be separate pieces stitched together on the dotted lines 6^d, so as to thereby 65 form a single sheet. The back forming portion 6^a, at its upper edge, is provided with a neck forming notch 7 and with rounded edges at 7^a. The front forming sections 6^b are provided with neck forming 70 notches 8 and with curved shoulder forming edges 8^a. The curved shoulder forming edges 8^a are formed by cutting out darts between the shoulder forming strips 6^c, and the upper ends of the front forming portions 6^b; and the curved edges 7^a are formed by cutting out darts between the flap 6^c 75 and the back forming portion 6^a.

The shoulder is formed by stitching the curved edges 7^a and 8^a to the adjacent edges 80 of the coöperating shoulder forming strips 6^a. The seams which connect these edges are preferably of the well known French seam type best illustrated in Figs. 4 and 5, wherein the said seams are indicated by the 85 numeral 9.

When the edges 7^a and 8^a are stitched to the edges of the shoulder forming strips 6^c, as stated, the neck of the garment will be formed by the notches 7 and 8 and by 90 the upper edges of the shoulder forming strips 6^c. Preferably, the edges of the shoulder forming strips 6^c are parallel, although their edge lines may be varied somewhat. The shoulder forming strips, 95 however, should be narrow and long portions primarily separated from the back and front forming portions of the garment, except at their lower ends.

The flaps or front forming portions 6^b are 100 adapted to be overlapped, as shown in Fig. 2, and connected by suitable buttons and operative buttonholes 10. The bottom of the garment may be either open or closed, but in some infants' garments, will usually be 105 closed. A suitable hood 11 is stitched onto the edges of the neck forming notches 7 and 8.

A garment with the shoulder structure described can be made from a minimum of 110 cloth or with a minimum of waste in the cloth from which it is made. Where the

cloth from which the garment is to be made is of the proper width, the entire body of the garment may be made from a single piece.

5 This improved shoulder, because of the nature of its construction and appearance, I designate as a French shoulder. It will be noted that the improved shoulder has no 10 seams directly on the top of the shoulder, but that it is formed with two seams, the one located forward and the other rearward of the top of the plane of the central line 15 of the shoulder. This not only gives better wearing qualities, but a better shape and neater appearance to the shoulder.

What I claim is:

1. A garment body comprising back and front forming portions and shoulder forming strips, the said strips at their lower ends 20 being integrally attached to the garment body, the edges of said shoulder strips and the upper adjacent edges of said front and back forming portions being brought together and united by stitching, the said shoulder strips forming a component part of the 25 garment proper and the extreme upper portions of said back and front portions and shoulder strips being cut to form the neck of the garment.

30 2. A garment body comprising back and front portions and shoulder forming strips,

the said strips at their lower ends being integrally attached to the garment body, the edges of said shoulder strips and the upper adjacent edges of said front and back 35 forming portions being brought together and united by stitching, the said shoulder strips forming a component part of the garment proper and the extreme upper portions 40 of said back and front portions and shoulder strips being cut to form the neck of the garment, and a hood stitched to the upper edges of said back and front and shoulder strips.

3. A sleeveless garment having front and 45 back forming portions and shoulder forming strips all cut from a single piece of cloth, there being primarily flaring gaps between the edges of said shoulder strips and the back and front forming portions 50 of the garment, said flaring edges being brought together and connected by stitches so that said integral shoulder strips constitute a component part of the garment and the top portions of the shoulders thereof. 55

In testimony whereof I affix my signature in presence of two witnesses.

REGINA L. PARENT.
